UNITED STATES PATENT OFFICE.

EUGENE C. CLARKE, OF CHAMBERSBURG, PENNSYLVANIA, ASSIGNOR TO CHAMBERSBURG ENGINEERING COMPANY, OF CHAMBERSBURG, PENNSYLVANIA, A CORPORATION OF PENNSYLVANIA.

PUNCHING MACHINE.

Application filed January 19, 1922. Serial No. 530,308.

To all whom it may concern:

Be it known that I, EUGENE C. CLARKE, a citizen of the United States, residing in Chambersburg, Pennsylvania, have invented 5 Punching Machines, of which the following is a specification.

My invention relates to punching and like machines, the main object of the invention being the provision in machines of this type 10 of improved and simplified means for facilitating the accurate location of the tool upon the work.

In the attached drawings:

Figure 1, is a side elevation of a punching machine of the vertical type made in accordance with my invention;

Fig. 2, is a fragmentary longitudinal sectional view illustrating the details of my invention;

Fig. 3, is a view similar to Fig. 2, further illustrating the operation of the device, and

Fig. 4, is a plan view of one of the stop elements.

With reference to the drawings, 1 indicates the frame of the machine, in which is mounted in the usual manner a sliding head 2. Carried by the sliding head 2 is a detachable punch block 3, said block having in the present instance a vertical recess 4 extending thereinto from the nether surface, said recess being cylindrical in form and having its mouth 5 restricted, as clearly shown in Figs. 2 and 3. Within the recess 4 is established a punch stock 6, said stock 25 being of such diameter as to pass neatly through the mouth 5 of the recess and having an extension or flange 7 on that part which occupies the main chamber of the recess 4, which prevents withdrawal of the 30 stock through the mouth 5. A spring 8 is shown, in the present instance, established between the top of the recess 4 and the upper surface of the flange 7, said spring tending at all times to force the stock 6 into the bottom of the recess.

In vertical punches, such as that illustrated herein, this spring may, if desired where the stock is sufficiently heavy to insure its falling to the bottom of the recess 45 under the force of gravity, be eliminated,

the spring or its equivalent being essential, however, in horizontal punches. The punch stock 6 is adapted in the usual manner to carry the tool or punch 6^a, and the usual anvil 1^a is provided for supporting the work, 55 which latter in the present instance is indicated by the reference numeral 9, in position to be operated upon by the said tool. The usual stripper 10 is shown by means of which the work is stripped from the punch 60 on its upward stroke.

Extending through the side of the punch block 3 and into the recess 4 is an opening 11, in which is slidably mounted a rod 12, the outer end of the rod being attached to one 65 arm of a bell crank lever 13 pivotally secured at 14 to the punch block 3. Extending downwardly from the frame 1 is a stud 15, to which stud are adjustably secured by means of set screws 16, 16, a pair of stops 17 and 18, 70 said stud and stops being so positioned as to lie in the path of the outer end of the arm 13^a of the bell crank lever 13 as it is vertically reciprocated with the punch block 3.

Figs. 2 and 3 illustrate the cycle of operations when my device is employed for facilitating the location of the punch on the work. In Fig. 2, the head 2 of the punch has been elevated to the top of its stroke, and the stop 17 is so positioned upon the stud 15 75 that with the head in this position the lever 13 has been engaged by the said stop 17 and the rod 12 withdrawn from the recess 4, this withdrawal of the rod 12 having the effect of releasing the stock 6 and permitting it to 80 drop under the action of gravity or the pressure of the spring 8 until the punch rests upon the work 9. With the tool resting upon the surface of the work in this manner, it is only necessary for the operator of the 85 machine to shift the work until the teat 7^a of the punch enters the desired counter-punch indicating the center of a hole to be formed in the work. With the downward movement of the head 2, the punch stock remains still until the top wall of the recess 4 90 engages the top of the stock, after which continued downward movement of the head forces the punch through the plate.

During the actual punching operation, the 100

lever 13 comes into engagement with the lower stop 18 upon the stud 15, which has been positioned for the purpose, whereby the rod 12 is moved inwardly so that it projects into the recess 4 below the flange 7, as shown in Fig. 3. In the ensuing upward motion of the head 2, the pin 12 prevents movement of the stock relative to the block 3, said rod retaining the stock in the top of the recess 4 until the lever 13 again engages the upper stop 17. During the period of time that the stock 6 is being elevated after the punch is stripped from the hole, the operator may shift the work 9 until he has brought into a position approximately under the punch a new area in which it is desired to form a hole, so that the final adjustment of the work to bring it into the exact position relative to the tool, which is accomplished after the stock has been released and while the tool rests upon the upper surface of the plate, is a comparatively slight one. As shown in Fig. 4, the upper stop 17 is flattened at one side, so that when this flattened portion is turned towards the bell crank lever 13, the latter will clear the stop, the rod 12 accordingly remaining in the advanced position and retaining the stock 6 in the top of the recess. The punch thus remains fixed and immovable in the head.

I claim:

1. The combination with a frame, of a head slidable therein, means for reciprocating said head, a tool carried by the head and movable with respect thereto, an element movably mounted in the head and adapted in one position to engage and retain the tool immovable therein and in another position to disengage the tool, a second element movably mounted on the head and connected with the retaining element, and a pair of spaced elements carried by the frame and adapted to engage the said second element at opposite ends of the stroke of said head to actuate the retaining element in different directions.

2. The combination with a frame, of a head movably mounted in said frame, means for reciprocating said head, said head having a recess, a tool-carrying element mounted in said recess and capable of free movement therein with respect to the head, a spring tending to retain the tool-carrying element in one end of said recess, means movably mounted in the head for retaining the tool-carrying element in the opposite end of said recess, and means operable at the end of each stroke of the head for actuating said retaining means to alternately engage and disengage the tool-carrying element.

3. The combination with a frame, of a head movably mounted in said frame, means for reciprocating said head, said head having a vertical recess extending inwardly from the under side thereof, a tool-carrying ele-

ment mounted in said recess and capable of limited vertical movement therein, means movable in the head for retaining the tool-carrying element in the upper end of the recess, and means operable at the top and bottom of the stroke of the head for actuating said retaining means to alternately engage and disengage the tool-carrying element.

4. The combination with a frame, of a head slidable therein, means for reciprocating the head, a tool carried by the head and movable with respect thereto, an element movably mounted in the head and adapted in one position to engage and retain the tool immovable therein and in another position to disengage the tool, a second element movably mounted on the head and connected with the retaining element, and a pair of spaced elements adjustably mounted upon the frame and adapted to engage the said second element at opposite ends of the stroke of said head to actuate the retaining element in different directions.

5. The combination with a frame, of a head movably mounted in said frame, means for reciprocating said head, said head having a recess, a tool-carrying element mounted in said recess and capable of free movement therein with respect to the head, means tending to retain the tool-carrying element in one end of said recess, a member slidably mounted in the head and adapted to enter the recess and engage the tool-carrying element to retain it in the opposite end of said recess, a bell crank lever pivotally mounted on the head and connected with said member, and a pair of spaced elements carried by the frame in position to be engaged by the bell crank lever respectively at top and bottom of the stroke of the head for actuating the pin to alternately engage and disengage the tool-carrying element.

6. The combination with a frame, of a head mounted in said frame, means for reciprocating said head, said head having a recess, a tool-carrying element mounted in said recess and capable of free movement therein with respect to the head, means for retaining the tool-carrying element in the recess, means tending to advance the tool-carrying element to the outer end of the recess, means for retaining the tool-carrying element in a retracted position in the recess, and means for actuating said retaining means to engage the element at the forward end of the stroke of said head and to release the element at the rear end of the stroke.

7. The combination with a frame, of a head slidable therein, means for reciprocating said head, a tool carried by the head and movable with respect thereto, an element movably mounted in the head and

adapted in one position to engage and retain the tool immovable therein and in another position to disengage the tool, a second element movably mounted on the ⁵ head and connected with the retaining element, a pair of spaced elements carried by the frame and adapted to engage the said

second element at opposite ends of the stroke of said head to actuate the retaining element in different directions, and means ¹⁰ for adjusting one of said spaced elements to prevent engagement thereof by said second movable element.

EUGENE C. CLARKE.
